(57) CLAIM

The ornamental design for a brassiere with padding pockets, as shown and described.

DESCRIPTION

FIG. 1 is a front perspective view of a brassiere with padding pockets showing my new design;

FIG. 2 is a back right perspective view thereof showing a right internal pocket opened;

FIG. 3 is a back left perspective view thereof showing a left internal pocket opened;

FIG. 4 is another back right perspective view thereof showing the right internal pocket closed;

FIG. 5 is another back left perspective view thereof showing the left internal pocket closed;

FIG. 6 is a front view thereof;

FIG. 7 is a back view thereof;

FIG. 8 is a right side view thereof;

FIG. 9 is a left side view thereof;

FIG. 10 is a top view thereof;

FIG. 11 is a bottom view thereof; and,

FIG. 12 is another back left perspective view showing the brassiere with padding pockets in use.

The broken lines in FIGS. 1-12 represent portions of the brassiere with padding pockets that form no part of the claimed design.
